UNITED STATES PATENT OFFICE.

FRANK J. VLCKEK, OF CLEVELAND, OHIO.

VALVE-SPRING LIFTER.

1,159,626.

Specification of Letters Patent.

Patented Nov. 9, 1915.

Application filed March 21, 1914. Serial No. 826,203.

To all whom it may concern:

Be it known that I, FRANK J. VLCKEK, a citizen of the United States, residing at Cleveland, in the county of Cuyahoga and 5 State of Ohio, have invented certain new and useful Improvements in Valve-Spring Lifters, of which the following is a specification.

This invention relates to a tool for relieving the tension of the coiled spring around the valve stem of an internal combustion engine to permit the removal of the valve.

The principal object of the invention is 15 to provide a valve spring lifter which is of simple practical construction and inexpensive to manufacture, and is very efficient for accomplishing the above stated purpose, the tool being so designed that a powerful cam 20 action is obtained for releasing the tension of the coiled spring with comparatively little effort on the part of the one using the tool.

With the above and other objects in view 25 as will be readily understood, the invention will be hereinafter fully described in connection with the accompanying drawings, which illustrate a preferred embodiment thereof, and the novel features of the invention will then be distinctly pointed out in the appended claim.

In the drawings like characters of reference indicate corresponding parts.

Figure 1 is a side view of a valve spring 35 lifter constructed in accordance with my invention, showing the same in position for relieving the tension of the valve spring, Fig. 2 is a plan view of the tool, Fig. 3 is an enlarged fragmental portion, partially in 40 section, illustrating the cam action feature of the tool, and Fig. 4 is a sectional view on line 4—4 of Fig. 3.

Referring to the drawings, 1 represents a portion of an internal combustion engine, 2 45 the exhaust valve supported by a stem 3, and 4 a coiled spring surrounding the valve stem. A cotter pin 5 fixed in the valve stem at a suitable position is adapted to support a cupped washer 6 for carrying said coiled 50 spring to cause the same to exert the necessary tension on the valve. The lower end of said valve stem is slidably mounted in a stationary support 7, and is adapted to be engaged by the usual rotatable cam for actuating the valve.

The tool herein set forth and described is

designed to compress the coiled spring 4 for relieving the tension on the valve, so that the cotter pin 5 may be easily withdrawn and the cupped washer 6 removed to permit 60 the ready removal of the valve, or after replacing the valve, the washer may be restored to its proper position and the cotter pin conveniently inserted.

The valve spring releasing tool consists 65 of a pair of complementary levers 8 and 9, having corresponding outwardly curved ends 10, which are pivotally connected at 11 between pairs of lugs 12 of a transverse head 13. Said levers are slightly tapering 70 in width from their attached ends to their free ends, which terminate in flattened and forked members 14, for straddling the valve stem 3. The forked members 14 have sharp noses, indicated at 15, to permit easy and 75 quick insertion of the tool in its application for releasing the tension on the coiled spring.

The levers 8 and 9 are forced apart by operating a handle 16 formed integral with 80 a threaded rod 17, which is rotatably mounted in the transverse head 13. The inner end of said threaded rod is reduced in diameter as shown at 18, thereby leaving an annular shoulder 19. Swiveled to said reduced portion 85 is a longitudinally reciprocating cross cam 20, which is provided with a boss 21 for receiving the thrust of the shoulder 19. The projecting end of said threaded rod is further reduced and threaded at 22 for receiving a stop nut 23 to retain the cam on the rod. Said cam is slidably connected to the before mentioned outwardly curved end portions 10 of the levers 8 and 9, for actuating the same, by means of suitable transverse cam slots 25, the inner walls 26 of which correspond to and are adapted to engage the inner edges 27 of said curved end portions. The outer walls 28 of the cam slots 25 are adapted to engage the outer 100 edges 29 of the curved end portions of the levers for forcing the levers to their closed position. Said outer walls 28 of the cam slots are chamfered or rounding as shown to allow free sliding movement of the cam 105 upon the levers.

In order to permit ready assembling of the levers 8 and 9 within the cam slots 25, portions of the cam above the slots are removed, as shown at 30, but overlapping 110 edges 31 are left to retain said levers within said slots. The width of the openings be-

tween the ends 32 of the edges 31 and the outer walls 28 of the cam slots is of a size sufficient for admitting the narrower tapering portions of the levers. When the levers 5 are thus placed within the slots and the cam is slidably moved to its proper position, the outwardly curved end portions 10 being of greater width than the width of the openings to the cam slots, they are retained 10 therein by the overlapping edges 31 of the cam.

It will be obvious that the herein described valve spring releasing tool is convenient to adjust between the end coil of 15 the coiled spring 4 and the stationary support 7; and that by comparatively little manual exertion in operating the handle 16, great power will be transmitted by the cam 20 to the outwardly curved end portions 10, 20 and the levers 8 and 9 will be forced apart to compress the spring. The cupped washer 6 may then be lifted up, the cotter pin 5 withdrawn, and the valve 2 easily removed. By turning the handle in the opposite direction, when the tool is in use, the levers 25 will be permitted to close preparatory to removing the tool; or by the same operation of the handle, the levers may be brought together by the action of the cam.

Copies of this patent may be obtained for five cents each, by addressing the "Commissioner of Patents, Washington, D. C."

Although the embodiment of the invention as illustrated and described will accomplish the intended purpose, it is to be understood that slight changes in the details of construction may be made within the scope of the claim. 30

Having fully described my invention, what I claim is:

In a valve spring lifter, the combination of a pair of levers, a head, the levers being pivotally connected to the head, the levers 40 being tapering in width, a cam, the cam having slots for receiving the wide portions of the levers, the cam being provided with openings in one side thereof less in width than the wide portions of the levers and 45 leading to the slots for admitting the narrower portions of the levers but leaving overlapping edges for retaining the wide portions of the levers in the slots, and means for operating the cam to actuate the levers, 50 substantially as described.

In testimony whereof I affix my signature in presence of two witnesses.

FRANK J. VLCHEK.
